CLAIM

The ornamental design for a pool table, as shown and described.

DESCRIPTION

FIG. 1 is a perspective view of a pool table showing my new design;

FIG. 2 is a perspective view thereof, showing undisclosed sides in FIG. 1;

FIG. 3 is a right side elevational view thereof, the left side elevational view being a mirror image thereof; and, FIG. 4 is a front elevational view thereof, the rear elevational view being a mirror image thereof.

The bottom is plain and unornamented.

FIG. 1

FIG. 2

FIG. 3.

FIG. 4.
